Filed July 24, 1969, Ser. No. 18,381

Term of patent 14 years

Int. Cl. D24—01, 05

U.S. Cl. D83—1

FIG. 1 is a side elevation of a urinator assembly or similar article showing my new design;

FIG. 2 is an extended view of the urinator assembly;

FIG. 3 is a side elevational view of the urinator assembly similar to FIG. 1, but showing it in the use position with the cap open;

FIG. 4 is a top plan view thereof, showing the empty neck without the filter, as seen from the line 4—4 of FIG. 2; and

FIG. 5 is a top plan view similar to FIG. 4, but with the filter seated.

Portions of the urinator assembly are fragmentarily broken away and shown in section for clarity of illustration.

I claim:

The ornamental design for a urinator assembly or similar article, substantially as shown and described.
